(57) **CLAIM**

The ornamental design for a spout with sensor, as shown and described.

DESCRIPTION

FIG. 1 is a perspective view of the top, front and right side of a spout with sensor showing our new design;

FIG. 2 is a front view thereof;

FIG. 3 is a rear view thereof;

FIG. 4 is a top plan view thereof;

FIG. 5 is a bottom view thereof;

FIG. 6 is a right side view, a left side view being a mirror image thereof; and,

FIG. 7 is an ended view at 7—7 in FIG. 6 thereof.

The broken lines represent the portions of the design that form no part of the claimed design.
